Des. 211,744

Patented July 23, 1968

211,744

COMBINED TABLE LEG AND BRACE UNIT

Howard Alan, 1707 N. Fern Court,
Chicago, Ill. 60614

Filed Mar. 15, 1967, Ser. No. 6,233

Term of patent 14 years

(Cl. D33—14)

I claim:

The ornamental design for a combined table leg and brace unit, as shown.
